UNITED STATES PATENT OFFICE.

McKEE D. HYNES, OF CHICAGO, ILLINOIS.

X-RAY TABLE AND THE LIKE.

Application filed January 31, 1923. Serial No. 616,196.

To all whom it may concern:

Be it known that I, **McKEE D. HYNES**, a citizen of the United States, residing at Chicago, in the county of Cook and State 5 of Illinois, have invented certain new and useful Improvements in X-Ray Tables and the like, of which the following is a specification.

This invention has to do with certain improvements in X-ray tables and the like. These tables are used for supporting persons undergoing X-ray examinations. The tables to which the present improvements particularly have reference are especially 10 intended for making X-ray photographs or similar exposures so as to establish a permanent record or one which can be examined in detail after the patient leaves.

Various portions of the human anatomy 20 are to be examined, including the different portions of the body itself as well as the head, arms and limbs. On account of the fact that some portions of the body are much thicker than others, and for other 25 reasons, the conditions under which the examination of the different portions should be conducted, vary within wide limits. Some portions require a much longer period 30 of exposure than others, and it has been found that the clearness and completeness of the exposure in examining some portions of the body is greatly improved by what is known as a **bucky diaphragm**. The bucky diaphragm includes a shutter or slat 35 like member which can be shifted across the field of illumination; and this diaphragm includes slats of materials whose permeability by the X-ray is different from that of the air to such an extent that the 40 travel of some of the rays is impeded without serious impediment to others. As a result, the time of exposure can be increased to the interval necessary to secure a clear impression from those rays which are hardest 45 to catch, without, however, allowing an excessive photographic action to take place by those rays which possess a higher actinism.

The action of this bucky diaphragm is 50 similar in some respects to that produced by a ray filter in certain other classes of photography.

In order to secure the best results when 55 using the bucky diaphragm, it is desirable to employ a construction of table or body support which has its top face curved about

the center from which the illuminating rays emanate. Consequently, there have been provided in the past X-ray tables equipped with suitable mechanism for producing the 60 photographic impression with the use of a so-called **bucky diaphragm**, which tables have a curved top or bed conforming to the characteristics above explained, and usually made of aluminum or the like. 65

There are many classes of X-ray examinations which do not require the use of the bucky diaphragm, but on the contrary, these other examinations can best be performed in the ordinary manner. For the 70 purpose of such an examination, it is only necessary to place the sensitized plate immediately behind that portion of the anatomy to be examined, so that the rays will directly impinge on the plate after passing through the anatomy. For the purpose 75 of such an examination, it is a very convenient and common expedient to place the plate on a flat table and then to place the patent immediately above the plate and in 80 contact therewith, directing the X-rays through the anatomy of the patient and onto the plate.

Owing to the fact that these X-ray tables are very expensive and occupy a considerable amount of space in the laboratory, it is very desirable to be able to use the same table and equipment for performing either class of examinations, that is, either by the use of the bucky diaphragm or without 85 its use. Consequently, there have been in the past devised bucky diaphragm tables which are provided with solid removable tops in the form of a single piece approximating the size of a door, which top 90 when in place on the table provides a bed for the patient when being examined without the use of the bucky diaphragm, and which top is bodily removed in order to expose the curved bed beneath it when it 95 is desirable to perform a bucky diaphragm 100 examination.

The above mentioned arrangement is extremely cumbersome and objectionable from numerous standpoints, including the fact 105 that it becomes practically necessary to employ the services of a special extra attendant for the purpose of removing and replacing this top according to the character of the examination to be performed. Further notable objection is that on account of its size, the manipulation of this table top is 110

objectionable since attending doctors patients, attendants, and friends or relatives present at the examination must in many cases move away from the table while the top is being removed or set into place. This tends to create confusion and detracts attention, both of which are very objectionable in any pathological laboratory.

The main object of my present invention 10 is to provide in combination with a bucky diaphragm table, an adjustable top therefor in the form of a flexible or collapsible partition of such nature and characteristics that it can be rolled or folded to either 15 remove it from the operating position or to reinsert it in place; said partition also being so mounted and supported that when in operating position it will effectively carry the weight of the patient; and also 20 that when removed it will pass into or away from the body portion of the table in a manner not requiring substantially more space than is occupied by the table itself.

A further object in connection with the 25 foregoing is to so arrange this partition that when it is moved into the inoperative position it will allow of the patient's reaching the bucky diaphragm support without material difficulty, and in fact in practically 30 as easy a manner as is possible with the old style of arrangement.

A further object of the invention is to 35 make provision for moving the partition into or out of working position by the use of a motor or other power mechanism, if desired; and in this connection to make provision for controlling the motor so as to either fully remove the partition from the 40 working position or fully restore it thereto by a simple switch operation and without the need of special thought or care on the part of the operator.

A further object of the invention is to 45 make provision for coupling the lamp stand to the bucky diaphragm if desired, so that the back and forth movements of these two parts can be properly harmonized when using the bucky diaphragm, notwithstanding the presence of the adjustable partition previously referred to.

Other objects and uses of the invention 50 will appear from a detailed description of the same, which consists in the features of construction and combinations of parts hereinafter described and claimed.

In the drawings:

Figure 1 shows a side view of an outfit embodying the features of the present invention, portions of the housing being broken away so as to better reveal the interior construction, and the lamp stand being broken away in order to reduce the size of the figure;

Fig. 2 shows a plan view corresponding to 65 Fig. 1, the partition being in working posi-

tion, but portions of the partition and portions of the housing therefor being broken away;

Fig. 3 shows a vertical section taken on the line 3—3 of Fig. 1, looking in the direction of the arrows;

Fig. 4 shows an end view of the apparatus looking in the opposite direction to Fig. 3;

Fig. 5 shows a fragmentary perspective view of two of the end slats, together with the connecting straps;

Fig. 6 shows a fragmentary detail view of a modified construction for supporting and driving the partition; and

Fig. 7 shows a section taken on the line 70 7—7 of Fig. 6, looking in the direction of the arrows.

The table illustrated in the drawings includes a suitable base or supporting section which includes the end brackets 8 and 9 respectively. A vertical mast or post 10 is provided which carries a bracket 11 upon which the X-ray apparatus 12 is located, the detailed construction of which it is unnecessary to explain in this application. 85 This bracket 11 is vertically movable upon the mast 10, being counter-balanced by a cord 13 or in any other suitable manner, so that it can be easily raised and lowered.

The mast itself is supported in an upright position by means of brackets 14 and 15, and these brackets are so carried and supported that the mast can be moved back and forth lengthwise of the table so as to present the X-ray apparatus directly to any 100 desired point on the table. For this purpose, I have illustrated a rail 16 extending horizontally between the lower portions of the brackets 8 and 9, and the bottom mast bracket 15 is mounted to travel with respect 105 to the rail 16. The bracket 14 is also mounted so that it can travel lengthwise with respect to the table while giving the mast proper support. The details of construction of these brackets are not illustrated, 110 since any suitable construction may be availed of.

The bucky diaphragm apparatus, and the 115 table surface upon which the patient is placed, are both carried by the upper portions of the brackets 8 and 9. The support for the bucky diaphragm apparatus is such that this apparatus can be shifted lengthwise of the table, and at the same time the arrangement is such that when desired, a removable partition can be drawn over the bucky diaphragm apparatus so as to provide a support for the patient independently thereof. I will now explain more in detail the particular construction illustrated for making 120 it possible to secure the results desired.

This particular construction includes a box like structure 17, preferably of sheet metal, having a floor 18 and side walls 19 and 20. Within this structure is placed the 130

bucky diaphragm apparatus 21, whose detailed construction it is not considered necessary to illustrate, since this type of apparatus is well known and understood in the art. I will state, however, that the bucky diaphragm includes a curved top or bed 22 upon which the patient may be placed and supported when the bucky diaphragm is being used. I will also state that the bucky diaphragm can be shifted lengthwise within the box like structure, being supported for this purpose in any convenient manner permitting such shifting to take place. The construction illustrated includes the side rails 23 and 24 located within the side walls 19 and 20 of the box like structure.

The side wall 20 includes a relatively large longitudinal opening 25 through which the bracket 14 reaches to the interior of the box like structure so as to establish the proper lateral support for said bracket while permitting the bracket to move lengthwise of the apparatus. A lug or finger 26 is provided for connecting the mast 10 with the bucky diaphragm apparatus, so that if desired, both the mast and the bucky diaphragm will be compelled to travel back and forth in unison. Nevertheless, this connection 26 may be disconnected so that either the mast or the bucky diaphragm can be shifted independently of the other.

I have provided a partition 27 which may be shifted with respect to the remaining portions of the apparatus so as to either cover over the bucky diaphragm and provide an independent support for the patient, or which partition may be readily moved away from such position so as to expose the bucky diaphragm and allow the same to be used for supporting the patient and making the examination.

In the particular construction illustrated, I have provided a longitudinally movable sectionized partition including cross slats 28 carried by a strip of canvas or other suitable flexible material 29, the slats 28 being placed close enough together to provide a substantially continuous supporting surface when laid out flat, but allowing the partition to bend or fold in passing over a roller or pulley, so that it can be readily shifted away from the working position into a location where it will be out of the way and at the same time allow the bucky diaphragm apparatus to be conveniently used.

The particular arrangement illustrated includes guide ways 30 and 31 for the end portions of the slats 28, permitting the slats to be shifted longitudinally of the table, but effectively supporting the end portions of the slats. The illustrated construction also includes pulleys 32, 33, 34 and 35 at the ends of the table over which the partition may be passed into the lower portion 36 of the box like structure previously referred to.

The strip 29 together with the slats 28 thereon occupy a length sufficient to effectively support the patient when the partition is fully drawn out, but the end portions 37 and 38 of this partition terminate at such points that the partition can be turned around in order to present an open or non-slatted portion above the bucky diaphragm apparatus so as to expose said apparatus and permit it to be used. For this purpose, the slatted portion is illustrated as being substantially the same length as the table itself, and the free ends of the member 29 are joined together by straps or strips 39 and 40 placed at the proper position to ride over the pulleys referred to. These straps 39 and 40 when used are placed close to the edge of the partition, so that the space between them is practically equal in width to the width of the bucky diaphragm itself.

Since the slats 28 are intended to support the weight of the patient lying on the center portion of the partition, said slats should be of sufficient rigidity to carry a substantial weight without appreciable bending. For this purpose I have shown each slat as being provided with a side plate 41 comprising a thin bar of metal and connected to the side of the slat by screws or any other convenient manner. These bars will provide the desired rigidity of structure while at the same time making it possible to have a partition presenting an almost continuous surface of wood with the attendant advantages.

Examination of Figs. 1 and 3 in particular will show the fact that the slatted portion of the partition can be retreated into a compartment 36 in the lower portion of the box like structure, which compartment is located beneath the track ways and supporting elements for the bucky diaphragm apparatus. This apparatus is in effect encircled or surrounded by the partition and its end connecting straps.

When it is desired to move the partition either into or out of the working position this can be accomplished in any convenient manner, either by hand or power. In the construction illustrated, I have shown an electric motor 42 placed within the box like structure and at one end thereof, and geared to the shaft 43 which extends between the pulleys 32 and 33, by means of gears 44 and 45. It is preferred that such motor and gearing when used should be located at a position where they will not interfere with a free movement of the bucky diaphragm into any service position. For this reason, I have illustrated these mechanisms as being located close to one end of the apparatus.

In the modified arrangement shown in Figs. 6 and 7, the use of cross shafts located centrally of the pulleys has been done away with, and instead, each pulley is carried by a bracket 46 secured to the box like struc-

ture itself. Each of these pulleys is also provided with an internal gear 47 and a cross shaft 48 located low down in the structure is provided, the same having a pinion 49 meshing with each of the internal gears of the opposite pulleys. In this case also a motor 50 is connected to the cross shaft 48 by a pinion 51.

This modified construction will in some cases present material advantages for the reason that when the bucky diaphragm apparatus is in use, the patient can more readily climb up onto the same by placing the shaft 48 as low down as possible.

15 The particular arrangement of partition illustrated in the drawings is movable longitudinally of the apparatus, and is adapted to retreat into the lower portion of a horizontally extending box-like enclosing structure. It will be understood, however, that as far as the essential feature of the invention is concerned, many other arrangements might be used without departing from the spirit of my present invention. For example, the partition might be constructed and mounted to travel transversely instead of longitudinally, and the flexible partition might be arranged to wind up on a drum or retreat into any other suitable place or enclosure than the particular one illustrated. Consequently, I do not intend to limit myself to the particular construction illustrated herein except as I may do so in the claims.

35 Any suitable controlling device may be used for controlling the operation of the electric motor to move the partition either into position above the bucky diaphragm or away from such position. For example, a 40 two point switch can be used for this purpose, which when thrown into one position will cause the motor to move the partition into working position, and which switch when thrown into the other position will 45 cause the partition to be moved away so as to expose the bucky diaphragm.

I claim:

1. In an X-ray table the combination of 50 a horizontally movable bucky diaphragm and patient support, a horizontally movable vertical lamp carrying mast adjacent thereto, separated pulleys at each end of the structure in line with the line of travel of the bucky diaphragm, a slatted flexible partition having its slats extending parallel to the axes of the pulleys and capable of flexure over the pulleys, means for supporting the edge portions of said partition to support the slats thereof when said slats are located above the position of the bucky diaphragm, said partition being adapted for travel over the pulleys aforesaid, the ends of the slatted portion of the partition being separated a substantial distance from each 65 other during its travel over the pulleys,

means for joining together the edges of said separated ends leaving an open space between said edges, and means for causing the partition to travel over the pulleys to carry either its slatted or its unslatted portion into 70 position above the bucky diaphragm, whereby when the slatted portion of the partition stands in the operative position above the bucky diaphragm a patient may be supported thereon for examination, and whereby when the unslatted portion of the partition is presented above the bucky diaphragm, a patient supported on the bucky diaphragm may be examined, substantially 75 as described.

2. In an X-ray table the combination of a horizontally movable bucky diaphragm and patient support, a horizontally movable lamp carrying mast adjacent thereto, rotary supports at each end of the structure 80 in line with the line of travel of the bucky diaphragm, a slatted flexible partition having its slats extending parallel to the axes of the pulleys and capable of flexure over the pulleys, means for supporting the edge portions of said partition to support the slats thereof when said slats are located above the position of the bucky diaphragm, said partition being adapted for travel over the rotary supports aforesaid, the ends of the slatted portion of the partition being separated a substantial distance from each other during its travel over the rotary supports, means for joining together the edges 85 of said separated ends leaving an open space 90 between the edges, means for causing the partition to travel over the supports to carry either its slatted or its unslatted portion into position above the bucky diaphragm, whereby when the slatted portion of the partition stands in operative position above the bucky diaphragm a patient may be supported thereon for examination, and whereby when the unslatted portion of the partition is presented above the bucky diaphragm a patient supported on the bucky diaphragm may be 95 examined, substantially as described.

3. In an X-ray table the combination of a bucky diaphragm and patient support, a vertical lamp carrying mast adjacent thereto, rotary supports at each end of the structure in line with the line of travel of the bucky diaphragm, a slatted flexible partition having its slats extending parallel to the axes of the pulleys and capable of flexure over the pulleys, means for supporting the edge portions of said partition to support the slats thereof when said slats are located above the position of the bucky diaphragm, said partition being adapted for travel over the rotary supports aforesaid, the ends of the slatted portion of the partition being separated a substantial distance from each other during its travel over the rotary supports, means for joining together 100

- the edges of said separated ends leaving an open space between the edges, means for causing the partition to travel over the supports to carry either its slatted or its unslatted portion into position above the bucky diaphragm, whereby when the slatted portion of the partition stands in operative position above the bucky diaphragm a patient may be supported thereon for examination, and whereby when the unslatted portion of the partition is presented above the bucky diaphragm a patient supported on the bucky diaphragm may be examined, substantially as described.
4. In an X-ray table the combination of a bucky diaphragm and patient support, a vertical lamp carrying mast adjacent thereto, a slatted flexible partition having parallel slats flexibly connected together and capable of flexure in a direction parallel to the slats at points intermediate between said slats and relatively rigid against flexure in a direction at right angles to the slats, means for supporting the edge portions of said partition to support the ends of the slats thereof when said slats are located above the position of the bucky diaphragm and thus afford a suitable support for the patient, rotary supporting means for the partition at one end of the apparatus, a suitable compartment to receive the partition when not in service, and means under the control of the operator for moving the partition either into said compartment to allow the patient to be directly supported with respect to the bucky diaphragm or into position above the bucky diaphragm as desired to afford support for the patient on the partition, substantially as described.
5. In an X-ray table the combination of a bucky diaphragm and patient support, a slatted flexible partition having parallel slats flexibly connected together and capable of flexure in a direction parallel to the slats at points intermediate between said slats and relatively rigid against flexure in a direction at right angles to the slats, means for supporting the edge portions of said partition to support the ends of the slats thereof when said slats are located above the position of the bucky diaphragm and thus afford a suitable support for the patient, rotary supporting means for the partition at one end of the apparatus, a suitable compartment to receive the partition when not in service, and means under the control of the operator for moving the partition either into said compartment to allow the patient to be directly supported with respect to the bucky diaphragm or into position above the bucky diaphragm as desired to afford support for the patient on the partition, substantially as described.
6. In an X-ray table the combination of a bucky diaphragm and patient support, a slatted flexible partition having parallel slats flexibly connected together and capable of flexure in a direction parallel to the slats at points intermediate between said slats and relatively rigid against flexure in a direction at right angles to the slats, means for supporting the edge portions of said partition to support the ends of the slats thereof when said slats are located above the position of the bucky diaphragm and thus afford a suitable support for the patient, a suitable compartment to receive the partition when not in service, and means under the control of the operator for moving the partition either into said compartment to allow the patient to be directly supported with respect to the bucky diaphragm or into position above the bucky diaphragm as desired to afford support for the patient on the partition, substantially as described.
7. In an X-ray table the combination of a bucky diaphragm and patient support, a flexible longitudinally movable partition capable of flexure across its length and capable of resisting ordinary loads against flexure parallel to its length, means for supporting the edge portions of said partition when located above the position of the bucky diaphragm and thus afford suitable support for the patient, a suitable compartment in the X-ray table to receive the partition when not in service, and means under the control of the operator for moving the partition either into said compartment to allow the patient to be directly supported with respect to the bucky diaphragm or into position above the bucky diaphragm as desired to afford support for the patient on the partition, substantially as described.
8. In an X-ray table the combination of a bucky diaphragm and patient support, a flexible partition capable of movement in a given direction with respect to the position of the bucky diaphragm, said partition being capable of flexure across said direction of movement and capable of resisting flexure at right angles thereto, means for supporting the edge portions of the partition when in place above the position of the bucky diaphragm and thus afford a suitable support for the patient, a suitable compartment in the X-ray table to receive the partition when not in service, and means under the control of the operator for moving the partition into either said compartment to allow the patient to be directly supported with respect to the bucky diaphragm or into position above the bucky diaphragm, as desired to afford support for the patient on the partition, substantially as described.

MCKEE D. HYNES.
